UNITED STATES PATENT OFFICE

FREDERICK W. NITTEL, OF ATTLEBORO FALLS, MASSACHUSETTS, ASSIGNOR TO M S CO.,
OF ATTLEBORO, MASSACHUSETTS

CONNECTER FOR BRACELETS

Application filed August 5, 1931. Serial No. 555,199.

This invention relates to certain new and useful improvements in bracelets and pertains particularly to bracelets of the expandable type, the primary object of the invention being to provide an improved form of flexible connection between the ends of the bracelet which connection may be easily and quickly manipulated for the purpose of removing or adding one or more links to the bracelet thereby to shorten or lengthen the same.

A further object of the invention is to provide a connection of this type which is of simple and economical construction, and which is composed of a minimum of parts that may be easily and quickly assembled without the use of solder or other extraneous fastening means.

The invention has further and other objects which will be later set forth and manifested in the course of the following description.

In the drawings:

Figure 1 is a front elevation of the invention applied to the ends of a bracelet;

Figure 2 is a rear side elevation.

Figure 3 is a section on line 3-3 of Figure 1;

Figure 4 is a section on line 4-4 of Figure 3, and

Figure 5 is a detail perspective view of the cover plate for the springs.

In proceeding in accordance with the present invention, a link 1 is employed which has inwardly extending guides 2 formed on the inner faces of its sides. Members composed of parts 3 and 4 hinged together at 5 are provided. The member 3 is formed with an in-turned lip 6 which engages the guides 2 at its ends and is formed with an opening 7 that is spaced from the hinge 5. A pair of substantially V-shaped springs 8 having central coils 9 are employed, the springs having a crossed relation and being disposed adjacent to the member 3 and therefore are located within the link 1. The outer ends of the springs engage in openings 10 provided therefor in the outer end of the link 1 while their opposite ends engage in openings 11 formed in a flange 12 which latter extends downwardly from one end of a cover 13. The flange 12 is provided with a lug 14 which latter is extended through

an opening provided therefor in the part 3 and is turned outwardly as shown in Figure 3 in order to clinch same in position. The opposite end of the cover is provided with a similar flange 15 having a hook-shaped part 16 which latter extends through the opening 7 in the part 3. It will thus be seen that the part 3 and the cover 13 form a housing for the springs 8. The part 4 is provided with knuckles 17 which are formed to snap over the lip 6 of the part 3. A finger engaging projection 18 is formed on the part 4 so as to facilitate unlatching of the knuckles 17. By referring to Figure 4 of the drawings it will be seen that the end 19 of the endmost link at the opposite end of the bracelet is engaged between the flange 15 and the hinge 5, so that upon moving the member 4 to the open position shown in Figure 4 the end 19 of the link can be easily removed or applied as desired.

From the foregoing it will be seen that the flexible connecter is composed of a hinged member formed of the parts 3 and 4 which due to their hinging action enable the endmost link at the opposite end of the bracelet to be easily and quickly attached to the connecter and at the same time the part 3 of the connector carries the spring means, whereby the connecter is rendered extensible.

Having thus described my invention what I claim as new and desire to secure by Letters Patent is:

1. In a bracelet, a link, members composed of two parts hinged together at one end, the free end of one of said parts having an in-turned lip, inner guides on the sides of the link engageable with the side edges of the lip, substantially V-shaped springs arranged in crossed relation within the link and each having one of their ends engaged with the adjacent end of the link, a cover for the springs having a flanged end formed with openings to receive each of the opposite ends of the springs, one part of the hinged members having an opening spaced from the hinge and the flange of the cover having a lug received in said last named opening means to latch the other end of the cover to said part of the hinged member, and means to latch said parts of the member together.

2. In a bracelet connecter, a link having guides, a pair of plates hinged together at one end and one of which has parts engaged with the guides, a cover of plate form between said parts, spring means between one of the plates and the cover and connected to the link, means carried by said cover plate and connected to the spring means, one of the hinged plates having a free end which extends over the adjacent end of the other hinged plate, and means to latch said free end of the first named hinged plate to the second named hinged plate, the plates and cover being all disposed in parallelism.

15 3. In a bracelet connecter, a link having guides, a pair of elements hinged together at one end and one of which has parts engaged with the guides, a cover between said elements, spring means between one of the 20 elements and the cover and connected to the link, means carried by said cover and connected to the spring means, and means independent of the spring means to latch the opposite ends of the said pair of elements together.

25 4. In a bracelet connecter, a link having guides, a pair of parts hinged together at one end and one of which has portions engaged with the guides, one of said parts having an end portion spaced from the inner side of the hinge to provide a link receiving space, a cover between said parts, spring means between one of the parts and the cover and connected to the cover and to the link, and means to latch the opposite ends of the 35 pair of parts together.

5. In a bracelet connecter, a link, a pair of elements hinged together at one end, means to latch the opposite ends of the elements to 40 one another, spring means housed by and between the elements and connected to the link, means to slidably connect said elements to the link, and a cover overlying and connected to the spring means and connected to one of the 45 elements, said spring means and cover being located between the ends of each of the elements, and said hinged element having its ends extending over the ends of the other element and the cover so as to house same.

50 6. In a bracelet connecter, a link having guides on the inner faces of its sides, members composed of two parts hinged together at one end, the free end of one of said parts having an inturned lip, the side edges of 55 which lip are engaged with the guides, a cover connected to one of said parts, an abutment carried by the cover, spring means connected to the abutment and to an end of the link to tension the member, and means to 60 latch the opposite ends of the two parts of the member together, one of said hinged parts having its ends extending over and across the ends of the cover and the other hinged part.

65 7. In a bracelet connecter, a link, members

composed of two parts hinged together at one end, the free end of one of said parts having an inturned lip, inner guides on the sides of the link engageable with the side edges of the lip, substantially V-shaped springs arranged in crossed relation within the link and each having one of their ends connected to the adjacent end of the link, a cover for the springs connected to each of the opposite ends of the cover to said first named part of the hinged members, and means to latch said parts of the members together.

In testimony whereof I have signed my name to this specification.

FREDERICK W. NITTEL.
